Seymour L. Jeruss, Bridgeport, Conn., assignor to
Noma Lites Corp., St. Joseph, Mo., a corporation
of Missouri

Filed Dec. 20, 1965, Ser. No. 247

Term of patent 14 years

(Cl. D29—1)

FIG. 1

FIG. 2

FIG. 3

FIG. 1 is a side elevational view of a Christmas tree light showing my new design;

FIG. 2 is a top plan view thereof, and

FIG. 3 is a perspective view thereof.

The essential features of my design reside in the portions shown in solid lines, namely the socket and faceted reflector; the fragmentary broken lines showing the electric cord in FIGS. 1 and 3 are for illustrative purposes only. The fragmentary broken lines showing an electric cord in FIGURES 1 and 3 are for illustrative purposes only.

I claim:

The ornamental design for a Christmas tree light, substantially as shown and described.
